OUTLET STRUCTURE FOR RAILWAY
HOPPER CARSGeorge B. Dorey, Westmount, Quebec, Canada, assignor
to Enterprise Railway Equipment Company, Chicago,
Ill., a corporation of Illinois

Filed Nov. 6, 1959, Ser. No. 851,459

7 Claims. (Cl. 105—282)

This invention relates to an improved outlet structure for a load containing hopper of the type employed in connection with railway hopper cars and the like for conveying finely comminuted lading.

The objects of the invention, among others, are: To provide improved sealing means around the edges of a sliding gate; to provide housing means for retaining gaskets in sealing position; to provide coordinating wedging means between a movable gate and hopper structure; and to provide a sealing gasket strip around the edges of a movable gate with provision for disposing the end portions of said sealing gasket strip in overlapping relation and thereby effect a double seal to coact with the projecting end of a sliding gate.

The invention further resides in certain details of construction and refinement of parts associated with the improved structure.

For further comprehension of the invention reference may be had to the accompanying drawings wherein the improvement is shown as applied to a railway hopper car.

In said drawings—

FIG. 1 is a vertical transverse elevational view of the lower portion of a hopper car showing approximately one half the width of the car with the improved structure applied thereto.

FIG. 2 is an elevational view of the structure shown in FIG. 1 as viewed from left to right.

FIG. 3 is a plan view of FIG. 2 showing the structure with the hopper walls eliminated and with certain parts broken away to better illustrate the construction.

FIG. 4 is a longitudinal elevational sectional view taken through the hopper on a line 4—4 of FIG. 1 and showing by conventional dot and dash lines the position of the parts with the gate in opened position.

FIG. 5 is a vertical sectional view taken on a line 5—5 of FIG. 2.

FIG. 6 is a fractional vertical sectional view on an enlarged scale taken on a line 6—6 of FIG. 3.

FIG. 7 is a fractional vertical sectional view on an enlarged scale taken on a line 7—7 of FIG. 3.

FIG. 8 is a fractional vertical sectional view on an enlarged scale as taken on a line 8—8 of FIG. 3.

FIG. 9 is a fractional vertical sectional view on an enlarged scale taken on a line 9—9 of FIG. 3.

FIG. 10 is a perspective sectional view of the gate.

In said drawings wherein the improvement is shown as applied to a railway hopper car, the car structure is indicated by a center sill 10 and side wall 11 having an edge angle 11a and interposed between said center sill and side wall is a four-sided hopper 12 having a discharge opening 13. In practice there are actually hoppers disposed on opposite sides of the center sill 10 in transversely aligned relation but inasmuch as the construction of the various hoppers is similar, the description herein will be confined to only one of such hoppers.

Each hopper 12 is formed in part by inner and outer side walls 14 and 15 which meet with oppositely sloping walls 16 and 17 to complete the four sides of a four-sided hopper. The marginal edges of the said walls 14, 15, 16 and 17 are spaced apart to form the discharge opening 13. The discharge opening 13 is closed by a sliding gate 18 which in turn is supported by a framing

2

structure 19. The framing structure 19 is formed in part by inner and outer longitudinally extending frame members 20 and 21 which are transversely united by frame cross members 22, 23 and 24.

5 The longitudinally extending frame members 20 and 21 include upper portions 25 and 26 which respectively overlie the inner and outer walls 14 and 15 and the cross member 22 likewise includes an upper portion 27 which overlies the sloping end wall 16. The cross members 23 and 24 are disposed at the end of the discharge opening 13 opposite to cross member 22 with cross member 23 disposed above the gate 18 to overlie sloping wall 17 of the hopper. The cross member 24 includes a vertical wall section 24' disposed below the gate 18 and flanged at its upper margin at 24" to underlie the gate 18. The flange 24" is spaced from the lower marginal edge 23' of the upper end wall 23 to define a slotted opening 28 through which the gate 18 slidably extends. The inner longitudinally extending frame member 20 preferably extends vertically above the gate 18 for attachment at 29 to the inner hopper side wall 14.

Horizontally disposed ledges 30, 31 and 32 of frame members 20, 21 and 22 form supports for the gate 18 in closed position and the said longitudinal frame members 20 and 21 are extended well beyond the slotted opening 28 at 33 and 34 to provide continuity of ledges 30 and 31 for supporting the gate 18 in opened position.

The gate 18 is beveled slightly, FIG. 10, as indicated at 35 to the extent shown at 35a at the leading end 36. 30 Longitudinally extending flanges 37—37 are provided at and secured to the sides of the gate 18 and they have their upper marginal edge surfaces 38 inclining downwardly from the trailing end 39 to the leading end 36 of the gate 18 to provide wedge shaped side flanges presenting the upper edge surfaces 38 inclined relatively to the gate bearing surfaces of ledges 30 and 31 of the rail members 20 and 21.

The trailing end portion 39 of the gate 18, which normally projects beyond the slot 28, is inclined on the underside to provide an end portion 41 inclined upwardly as indicated at 41a (FIG. 10) to extend in the direction of or parallel to the inclined surfaces 38. Secured to the upper surface of the end portion 39 is a reinforcing bar 42 which extends transversely of the gate 18 and is of such thickness as to dispose its upper surface 43 in alignment with and forming continuations of the edge surfaces 38 of the side flanges 37—37 and the beveled surface 35 at the leading end 36 of the gate 18. The said surfaces 35 and 38—38 in combination with surface 43 lie in a continuous common plane inclined relatively to the top surface of the gate 18 around its upper margins. Coacting with this marginal surface is a resilient gasket 44. The gasket 44 is preferably of hollow circular section and readily deformable to seat in receptacles as will be described.

55 The gasket 44 extends around the four sides of the discharge opening 13 and is of single ply on three sides of the opening as indicated at 45, 46 and 47 and on the fourth side provides for a two ply overlapping construction by having the two ends 48 and 49 overlap for substantially the entire width of the gate 18 (FIG. 3).

For holding the gasket 44 in place there are provided housings on three sides in the form of inclined shedding plates 50, 51 and 52 which receive the sections 45, 46 and 47. On the fourth side of the opening at the projecting or trailing end 39 of the gate 18 there is provided an angle shaped reinforcing member 53 having one wall 54 underlying the upper transverse wall 23 and the other wall 55 outstanding therefrom. The two ends of the gaskets 48 and 49 are positioned in the angle formed by the walls 54 and 55 and held therein in

a deformed state by lugs 56 and 57 which are welded in place on the respective walls 54 and 55 to form restricted mouth openings therebetween.

Similarly the other gasket sections 45, 46 and 47 are held in place by lugs 58 for section 45, at 60 for section 46 and at 62 for section 47.

The gate 18 is preferably operated by toggle mechanism, generally indicated at 64, and which preferably consists of a rotatable shaft 65 mounted in bearings 66 at the outer ends of extensions 33 and 34. The toggle mechanism 64 includes arms 67—67 non-rotatably mounted on the shaft 65 and links 68—68 respectively pivoted at one end to the said arms at 69 and having their opposite ends pivotally connected to the gate 18 by pivots 70 which extend through lugs 71 secured to the trailing end 39.

The arms 66, in combination with their associated links 67, as shown by full lines in FIG. 4, assume a slightly over-center knuckled position thereby providing a toggle lock to force the gate 18 to tightly closed position against the resilience of the gasket 44.

The shaft 65 is rotated by a suitable operating head 72 having a series of openings 73 for the accommodation of a removable bar conventionally indicated at 74.

What is claimed as new is:

1. A discharge outlet assembly comprising, in combination,
  - (a) a foursided chute-like enclosure defining a discharge opening,
  - (b) a gate for said opening movable beyond one of the sides of said enclosure to open position,
  - (c) support means on opposite sides of said enclosure extending toward each other on which said gate is movable,
  - (d) said gate including an upstanding flange wall at each side extending in the general direction of movement of the gate and tapering in height from a location adjacent said one side of said enclosure when said gate is in closed position,
  - (e) ledge means along each of said opposite sides of said enclosure in overlying relation to the respective side flange of said gate,
  - (f) resilient gasket means interposed between the undersurfaces of said ledge means and the upper surfaces of said side flanges when said gate is fully closed, and
  - (g) means for moving said gate between open and closed positions.
2. The invention, as set forth in claim 1, wherein
  - (a) ledge means on the side of the enclosure opposite the side beyond which the gate is movable overlies the adjacent end of said gate in closed position,
  - (b) the upper surface of said gate at said adjacent end is coplanar with the surfaces of the coextensive portions of the flange walls, and

(c) resilient gasket means is interposed between the last mentioned ledge means and said upper surface of said gate in its fully closed position.

3. The invention, as set forth in claim 2, wherein

(a) the gate in fully closed position projects from the side of the enclosure beyond which it is movable,

(b) ledge means on the outside of the last mentioned side of the enclosure overlies the adjacent end of said gate, and

(c) resilient gasket means is interposed between the last mentioned ledge means and the underlying surface of said gate in its fully closed position.

4. The invention, as set forth in claim 3, wherein the resilient gasket means is tubular in character and is overlapped underneath the ledge means on the outside of the side of the enclosure beyond which the gate is movable to present double impingement surfaces for engaging the underlying surface of said gate in its fully closed position.

5. The invention, as set forth in claim 1, wherein

(a) the support means on which the gate is movable are runways on which said gate is slidable,

(b) the upper marginal edges of the upstanding flange walls are inclined in relation to the surfaces of said runways on which said gate slides, and

(c) the resilient gasket means is secured to the respective ledge means and impinges upon said upper marginal edges of said upstanding flange walls when said gate is fully closed.

6. The invention, as set forth in claim 5, wherein

(a) the gate in fully closed position projects from the side of the enclosure beyond which it is movable, and

(b) the projecting end of said gate is inclined upwardly at substantially the same angle of taper of the upstanding flange walls.

7. The invention, as set forth in claim 1, wherein the undersurfaces of the ledge means are inclined and in complementary relation to the upper surfaces of the side flanges.
